JOSIAH McFARLAND, OF CLINTON, ILLINOIS.

Assor to self & William W. Adams of the same place.

Letters Patent No. 79,140, dated June 23, 1868.

IMPROVEMENT IN FIRE-KINDLERS.

The Schedule referred to in these Letters Patent and making part of the same.

TO ALL WHOM IT MAY CONCERN:

Be it known that I, JOSIAH McFARLAND, of Clinton, in the county of De Witt, and in the State of Illinois, have invented a new and improved Fire-Kindler; and I do hereby declare that the following is a full, clear, and exact description thereof, reference being had to the accompanying drawings, and to the letters of reference marked thereon, which make part of this specification, and in which—

Figure 1 represents a top view of my improved fire-kindler, and

Figure 2 a side view, partly in elevation and partly in section, of the same.

The object of my invention is to provide a simple and convenient device for kindling fires with rapidity and safety, obviating the inconvenience of using shavings or other light combustible matter, and the danger attendant upon the ordinary use of inflammable fluids for that purpose; and to this end my improvement consists in arranging a bowl filled with plaster Paris, pumice-stone, saw-dust, or other porous substance, upon a suitable handle, and providing it with a perforated cup or burner, into which petroleum, benzine, or other inflammable fluid is to be introduced.

In the accompanying drawings, A represents the hollow bowl of the fire-kindler, which may be made of any desired form and suitable material, and which is secured upon a handle, C. This bowl is to be filled with plaster, soapstone, pumice-stone, saw-dust, or other porous substance, and has let into its top a shallow cup or burner, B, perforated with a number of small holes.

To kindle a fire with the apparatus, a handful of chips is placed near the draught or damper of a stove, and the wood or coal thrown in. Benzine, petroleum, or other inflammable liquid is then poured into the burner B, until the porous substance in the bowl is saturated with it. A match being then applied, and the kindler held near the opening of the draught, the inflammable liquid therein will burn with a steady heat, and completely ignite the wood or coal in from three to five minutes.

One or two teaspoonfuls of liquid will burn from ten to fifteen minutes, and the porous material in the bowl serves to diffuse it and prevent explosion.

The bowl may be made of any desired shape, and when provided with a supply-pipe, the apparatus answers admirably for a torch-light, which may be kept burning for any length of time, without risk of explosion.

What I claim as new, and desire to secure by Letters Patent, is—

The within-described fire-kindler or torch, having a hollow bowl, A, filled with porous material, and a perforated burner, B, as set forth.

In testimony that I claim the above-described improved fire-kindler, I have hereunto signed my name, this day of

1868.

JOSIAH McFARLAND.
